UNITED STATES PATENT OFFICE.

JOHN C. GABEL, JR., OF ONARGA, ILLINOIS.

SOAP-FEEDING ATTACHMENT FOR BRUSHES.

SPECIFICATION forming part of Letters Patent No. 727,780, dated May 12, 1903.

Application filed July 12, 1902. Serial No. 115,270. (No model.)

To all whom it may concern:

Be it known that I, JOHN C. GABEL, Jr., a citizen of the United States, residing at Onarga, in the county of Iroquois and State of Illinois, have invented certain new and useful Improvements in Soap-Feeding Attachments for Brushes, of which the following is a specification.

This invention relates to improvements in an attachment to be used for supplying soap to the bristles of brushes, and while it is more especially intended to be used on shaving-brushes, yet it is applicable to tooth-brushes, scrub-brushes, bath-brushes, and various other kinds; and it consists in certain peculiarities of the construction, novel arrangement, and operation of the various parts thereof, as will be hereinafter more fully set forth and specifically claimed.

The object of my invention is to provide an attachment for holding and feeding or supplying soap to the bristles of the brush in such a manner that the soap will not come in contact with the hand of the user, and which attachment shall be simple and inexpensive in construction, strong, durable, and effective in operation.

Another object of the invention is to so construct the device that when any one of its parts becomes defective or worn it can be replaced by a new or perfect one.

Still another object of the invention is to afford means for cutting and conveying or forcing the soap to the bristles.

Other objects and advantages of the invention will be disclosed in the subjoined description and explanation.

In order to enable others skilled in the art to which my invention pertains to make and use the same, I will now proceed to describe it, referring to the accompanying drawings, in which—

Figure 1 is a central vertical sectional view through a shaving-brush embodying my invention. Fig. 2 is a view in side elevation, showing the attachment applied to an ordinary scrub-brush. Fig. 3 is a plan view taken on line 33 of Fig. 1, showing the bristle-holder and soap-supplying tube. Fig. 4 is a top plan view of the funnel-shaped tube and its knife or cutter. Fig. 5 is a detached perspective view of the flexible tube and its coupling.

Fig. 6 is a detached vertical sectional view of the funnel-shaped tube, showing the construction thereof; and Fig. 7 is a plan view of the same.

Similar letters refer to like parts throughout the different views of the drawings.

A represents the bristle-holder, which is preferably cylindrical and has secured thereto in any suitable manner a series of bristles a, of any desired material. The upper portion of the holder A is provided with a central screw-threaded opening a' to engage external screw-threads on the cylindrical piece B, which has at its upper end an annular flange b, provided on its exterior with screw-threads to engage internal screw-threads on the soap-holder C, which has at its upper end an annular flange c, which is preferably milled, as shown, so that it may be easily turned. The upper inner portion of the piece B, which connects the soap-holder C and the bristle or brush holder A, is internally screw-threaded to engage the upper portion of the conveyer-tube D, which is preferably funnel-shaped, as shown, and has at its upper end an upwardly-curved blade d, which extends across the mouth or upper end of said tube. The lower end of the conveyer-tube D fits in the upper end of the discharging-nipple E, which is embedded in or surrounded by the bristles a and has at its upper end an annular flange e to rest on the top of the bristles, as is clearly shown in Fig. 1 of the drawings. The lower end of the nipple E extends to near the lower surface of the bristle or brush holder A and is externally screw-threaded to receive the screw-threaded coupling f on the flexible tube F, which is provided with a series of perforations f' and has its free end provided with slits f'', as shown, so as to prevent it being uncomfortable when pressed against the face of the user and also for the purpose of distributing the soap or lather through the bristles.

In Figs. 6 and 7 of the drawings I have shown the conveyer-tube D as being provided with a gimlet-shaped conveyer G, which comprises two blades g, secured at their lower ends to the lower inner surface of the tube D and having their upper portions spirally bent around one another and extending to near the top of said tube. It is apparent that I

may use the conveyer-tube without the blade *d* or may use the said blade and tube without the conveyer.

5 In Fig. 2 of the drawings I have shown the attachment applied to an ordinary scrub-brush, in which case the piece *A* acts as a holder for the brush-block *H*, as well as for a portion of the bristles of the brush.

From the foregoing and by reference to the 10 drawings it will be seen and clearly understood that by placing a quantity of soap *I* in the soap-holder *C* and screwing the latter down on the connecting-piece *B* the soap will be cut or shaved by the blade *d* and will pass 15 into the conveyer-tube *D* and from thence through the nipple *E* and flexible tube *F*, when used, to the bristles. By turning the soap-holder *C* farther down on the connecting-piece it is evident that the conveyer *G*, 20 by reason of its spiral blades and the pressure of the soap thereon, will force the cut portions through the discharging-nipple, thus rendering the action or operation of the device positive. When the attachment is applied to an ordinary scrub-brush, as well as 25 a shaving-brush, it is obvious that the soap will be protected from the hand of the user and that the attachment will form a convenient handle for using the brush, and as a small 30 quantity of the soap only is exposed to the action of the water used to make the lather it will not unnecessarily be wasted.

Having thus fully described my invention, what I claim as new, and desire to secure by 35 Letters Patent, is—

1. The combination with the bristle or brush holder, of a connecting-piece secured

to its upper portion, a soap-holder adjustably secured on the upper end of the connecting-piece, a discharging-nipple located in the bristle or brush holder, a conveyer-tube located in the connecting-piece and having means to cut the soap, substantially as described. 40

2. The combination with the bristle or brush holder, of a connecting-piece secured 45 to its upper portion and having its upper end externally screw-threaded, a soap-holder having internal screw-threads and secured on the upper end of the connecting-piece, a discharging-nipple located in the bristle or 50 brush holder, a conveyer-tube located in the connecting-piece, a transverse blade on the upper end of the conveyer-piece and a gimlet-shaped conveyer within the conveyer-tube below said blade, substantially as described. 55

3. The combination with the bristle or brush holder, of a connecting-piece secured to its upper portion and having its upper end externally screw-threaded, a soap-holder provided with internal screw-threads and secured on the upper end of the connecting-piece, a discharging-nipple located in the bristle or brush holder, a flexible perforated tube on the lower end of the nipple, a conveyer-tube located in the connecting-piece, a blade secured across the upper end of the conveyer-tube, and a gimlet-shaped conveyer located in said tube below the blade, substantially as described. 60 65
